UNITED STATES PATENT OFFICE.

RICHARD A. BEMIS, OF SAN BERNARDINO, CALIFORNIA.

WAVE-MOTOR.

1,097,073.

Specification of Letters Patent.

Patented May 19, 1914.

Application filed February 4, 1914. Serial No. 816,513.

To all whom it may concern:

Be it known that I, RICHARD A. BEMIS, a citizen of the United States, residing at San Bernardino, in the county of San Bernardino and State of California, have invented certain new and useful Improvements in Wave-Motors; and I do hereby declare the following to be a full, clear, and exact description of the invention, such as will enable others skilled in the art to which it appertains to make and use the same.

The primary object of this invention is to provide an extremely simple and practical wave motor, which shall constitute an improvement over my Patent No. 1,077,509.

Another and more specific object of the invention is to provide in a wave motor, an oscillating cylinder, a piston operable within said cylinder, a piston rod extending outwardly therefrom and having secured to its free terminal a plate to receive the force of the waves, and novel means for supporting the free end of the piston rod so that the plate will always remain substantially at the surface of the water so as to receive the full force and power of the waves.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a perspective view of my improved wave motor, parts thereof being shown in section, and Fig. 2 is a detail sectional view of one of the airtight floats.

Referring in detail to the drawings by numerals, 5 designates, as an entirety, a cylinder, mounted to oscillate between supporting legs 6 and formed with an intake port 8 and a discharge port 7, the former being surrounded by a nipple 9 housing a check valve 10, and the latter being provided with a check valve 11 opening in a direction opposite to the valve 10. A hose or flexible pipe 12 connects the nipple 9 with a storage tank 13 which may be located in any desired position.

A piston head 14 operates within the cylinder 5 and has connected to its outer face

a piston rod 15 which extends through a bearing 16 secured to the head 17 of the cylinder. A coil spring 18 surrounds the piston rod 15 and bears at one end against the head 17 and at its other end against the transverse pin 19 secured to the rod 15. This spring draws the piston head 14 toward the head 17 after it has been forced inwardly by the waves in a manner to be hereinafter described.

The piston rod 15 extends over a body of water and carries upon its free terminal a plate 20 against which the waves impinge as they roll inward and as they recede. At the ends of the plate 20, inwardly extending flanges 21 are provided and to the lower edges of these flanges I secure floats 22 which hold the plate normally in a substantially horizontal position, so as to best receive the action of the waves. To guide the piston rod 15 and support the lifting mechanism for the plate 20, I provide a pair of standards 23 which are driven into the earth on opposite sides of the rod near the outer end thereof. The upper ends of these standards are extended outwardly in a horizontal plane in spaced relation to form arms 24 between which a sheave or roller 25 is journaled on an axle 26. A flexible connection 27 runs over the sheave or pulley 25 and under a grooved pulley 28 supported under one of the arms 24 by an angular bracket 29. The outer end of the flexible connection 27 is connected by flanges 30 to the end of the plate 20, as clearly shown in the drawings.

A shaft 31 projects laterally from the upper end of one of the standards 23 and supports a pair of grooved rollers or pulleys 32 and 33. A second shaft 34 is connected to the last mentioned standard 23 directly under the shaft 31 below the surface of the water, and has journaled thereon a grooved roller or pulley 35 in the same vertical plane as the pulley 33. An endless cable or other flexible member 36 runs around the pulleys 33 and 34 and has fixed to one lead thereof a float 37. This float is formed with an opening 38 through which the other lead of the endless cable passes, so that the float when actuated by the rise and fall of the tide, will move in a vertical plane and be guided by the cable. A counterbalance weight 39 is secured to the lead 40 of the cable 36, and the inner end of the connec-

tion 27, after being passed over the pulley 83, is attached thereto. The connection 27 is of such a length as to hold the plate 26 in the same horizontal plane as the float 37, 5 and as this float always remains on the surface of the water, the plate will be in proper position to receive the full force of the waves.

In operation, waves impinging against 10 the plate 20, force the piston head 14 inwardly, causing the valve 10 to open and the valve 11 to close, whereby air is forced into the tank or reservoir 13. The spring 18 returns the piston 14 to its outward position 15 after a wave has passed by the plate 20, and the next wave again forces the piston head inwardly, and thus it will be seen that a continuous reciprocatory action of the piston takes place. As the float 37 rises with the 20 tide, the weight 39 will descend, causing an upward movement of the outer end of the connection 27 to raise the plate 20, and when the tide falls, a reverse action takes place. Brace rods 41 extend inwardly from 25 the flanges 21 and connect to a cross bar 42 secured to the rod 15 to brace the connection between the plate and rod.

While I have shown and described the preferred embodiment of my invention, it 30 will be understood that minor changes in construction, combination and arrangement of parts may be made without departing from the spirit and scope of the invention as claimed.

Having thus described my invention, I claim:

1. In a wave motor, an oscillating cylinder, a piston arranged within said cylinder, a piston rod, means on the end of said piston rod for receiving the impact of the waves, and means for guiding and supporting the piston rod comprising a pair of standards positioned on opposite sides of the piston rod within the water, an endless cable supported in a vertical plane by one of said standards, a float secured to one lead of the cable, a pulley journaled between the upper ends of said standards, and a flexible connection secured to the impact receiving

means and to the other lead of said cable, 50 the connection passing around the pulley.

2. In a wave motor, the combination of an oscillating cylinder, a piston arranged within said cylinder, a piston rod, means secured to the outer end of said piston rod for receiving the impact of the waves, and guide and supporting means comprising a pair of standards arranged in the water on opposite sides of the piston rod, said standards being formed with outwardly projecting arms on 60 their upper terminals, a sheave journaled between said arm, a pair of pulleys secured to one of said standards, an endless cable running around said pulleys, a float secured to one lead of the cable, and a flexible connection secured to the impact receiving means and to the other lead of the cable, said connection passing over the sheave.

3. In a wave motor, an oscillating cylinder, a piston arranged within said cylinder, 70 a piston rod, means on the end of said piston rod to receive the impact of the waves, a pair of standards arranged within the water on opposite sides of the piston rod and formed on their upper terminals with outwardly extending arms, a sheave journaled between the free terminals of said arms, a pair of shafts projecting laterally from one of said standards, a pair of pulleys secured to the upper of said shafts, a third pulley 80 secured to the lower of said shafts, an endless cable running around said last mentioned pulley and the corresponding pulley on the upper shaft, a float secured to one lead of said cable and having an opening 85 through which the other lead passes, a counterbalance weight secured to the cable on the second mentioned lead and a flexible connection secured to the impact receiving means and to said weight, the connection 90 passing over the sheave and one of the pulleys on the upper shaft.

In testimony whereof I affix my signature in presence of two witnesses.

RICHARD A. BEMIS.
